CLAIM

An ornamental design for a #1 fan cookie cutter, as shown and described.

DESCRIPTION

FIG. 1 is a perspective view of the #1 fan cookie cutter showing my new design.

FIG. 2 is a top view of FIG. 1.

FIG. 3 is a right side elevation view of FIG. 2.

FIG. 4 is a front elevation view of FIG. 2.

FIG. 5 is a bottom view of FIG. 1.

FIG. 6 is a left side elevation view of FIG. 5; and,

FIG. 7 is a front elevation view of FIG. 5.

The broken lines shown in FIGS. 1, 2, 3, 4, 5, 6 and 7 are for the purposes of illustrating and forms no part of the claimed invention.
